UNITED STATES PATENT OFFICE.

THOMAS C. JOHNSON, OF NEW HAVEN, CONNECTICUT, ASSIGNOR TO WINCHESTER
REPEATING ARMS CO., OF NEW HAVEN, CONNECTICUT, A CORPORATION.

FIREARM.

1,212,773.

Specification of Letters Patent. Patented Jan. 16, 1917.

Application filed October 23, 1916. Serial No. 127,077.

To all whom it may concern:

Be it known that I, THOMAS C. JOHNSON, a citizen of the United States, residing at New Haven, in the county of New Haven and State of Connecticut, have invented a new and useful Improvement in Firearms; and I do hereby declare the following, when taken in connection with the accompanying drawings and the characters of reference marked thereon, to be a full, clear, and exact description of the same, and which said drawings constitute part of this application, and represent, in—

Figure 1 a plan view of the breech-end of a gun-barrel constructed in accordance with my invention. Fig. 2 a view thereof in rear elevation. Fig. 3 a broken view in longitudinal section, showing the gun-barrel and breech-bolt with a cartridge in position in the cartridge-chamber of the barrel with its head engaged by the cartridge-extractor which is applied to the bolt. Fig. 4 a plan view of the forward end of the bolt. Fig. 5 a view thereof in front elevation.

My invention relates to an improvement in firearms of the class using rim-cartridges as distinguished from rimless cartridges, the object being to provide clearance in the gun-barrel for the cartridge-supporting abutment projecting from the forward end of the breech-bolt, without interfering with the support of the body and rim of the cartridge by the gun-barrel itself.

With these ends in view, my invention consists in a firearm having certain details of construction as will be hereinafter described and pointed out in the claim.

In carrying out my invention, as herein shown, I form a segmental, concentric clearance-recess 2 in the flat rear face 3 of the threaded stem 4 projecting from the breech-end 5 of the gun-barrel 6. The said clearance-recess 2 is separated from the cartridge-chamber 7 in the breech-end 5 of the gun-barrel, by a segmental cartridge-supporting wall 8 as best shown in Fig. 2. Under this construction, the provision of the gun-barrel

6 with the clearance-recess 2, does not impair the support afforded the cartridge by the walls of the cartridge-chamber 7. The 50 said clearance-recess 2 receives the beveled forward end of a cartridge-retaining abutment 9 projecting from the forward end of the breech-bolt 10 and co-acting in the usual manner with the cartridge-extractor 11 55 which is applied to the bolt and which enters a clearance-cut 12 in the face 3 aforesaid.

When the gun is closed with a rim-cartridge 13 in the cartridge-chamber 7, the cartridge-retaining abutment 9 enters the clearance-recess 2, the segmental form of which permits the abutment to move in the recess as the bolt is being rotated a quarter turn for locking and unlocking. When the breech-bolt is unlocked and retracted for the 65 extraction of the spent cartridge, the abutment 9 supports the cartridge through the rim thereof, against the thrust in the opposite direction of the extractor 11, throughout the extracting operation. The recess 2 thus 70 provides for the clearance of the abutment 9, while the wall 8 preserves the integrity of the outer edge of the cartridge-chamber 7.

I claim:—

In a firearm, the combination with a 75 breech-bolt adapted to be rotated for locking and unlocking it, and provided with a forwardly projecting cartridge-retaining abutment, of a gun-barrel formed with a segmental clearance-recess for the reception 80 and rotary movement of the said abutment, the said recess being separated from the rear portion of the cartridge-chamber in the gun-barrel by a cartridge-supporting wall, and a cartridge-extractor co-acting with the said 85 abutment in the extraction of the spent-cartridges.

In testimony whereof, I have signed this specification in the presence of two subscribing witnesses.

THOMAS C. JOHNSON.
